UNITED STATES PATENT OFFICE.

JOHN J. FINNIGAN, OF SELMA, ALABAMA.

SAFETY OIL-TANK.

SPECIFICATION forming part of Letters Patent No. 290,559, dated December 18, 1883.

Application filed November 2, 1883. (No model.)

To all whom it may concern:

Be it known that I, JOHN J. FINNIGAN, a citizen of the United States, residing at Selma, in the county of Dallas and State of Alabama, 5 have invented certain new and useful Improvements in Safety Oil-Tanks, of which the following is a specification, reference being had therein to the accompanying drawings.

This invention relates to certain improvements in tanks or holders for liquid hydrocarbons and other volatile and inflammable liquids; and it has for its objects to provide for the escape of the gases or vapors generated from or arising from the liquid contents of the 10 tank in such manner that if ignited on the outside the fire will not be communicated to the interior in case of a contained explosive mixture of air and gas or vapor, and also to prevent the tendency of such explosive mixtures 15 by excluding the air, as more fully herein-after specified. These objects I attain by the means illustrated in the accompanying drawing, in which is represented a vertical sectional view of a tank or holder showing my 20 invention applied thereto.

The letter A indicates a metallic tank of the usual construction, provided with a man-hole and cover, B, near its bottom.

The letters C and D indicate the induction 25 and eduction pipes through which the liquid is supplied to and discharged from the tank. These pipes are provided with suitable valves, by means of which the flow of liquid may be regulated and controlled.

The letter C' indicates a cylindrical chamber 30 mounted upon the upper end of a tube, D', secured to the top of the tank, the chamber and tank communicating with each other through the said tube. Within the lower 35 part of the chamber over the upper end of the tube, is located a concavo-convex disk, E, of perforated metal or wire-gauze, and above this a series of rings, F, with intervening perforated disks, G, the rings being flanged and 40 secured together in any convenient manner, and upon the chamber is secured a flat perforated cap, H, for the purpose hereinafter explained. The spaces between the perforated 45 disks are packed with granulated material—such as sand, gravel, broken stone, or other 50 similar substance—for the purpose hereinafter explained.

I indicates a cylindrical casing of perforated metal or wire-gauze, which sits loosely over

the chamber, and which is provided with a 55 flat top, K, and a conical hood, L, the latter being for the purpose of shedding rain. To the top of the hood is secured one end of a chain, M, which passes over a pulley, N, at the end of a standard, P, on top of the tank. 60 The other end of the chain is carried down the side of the tank, and may be secured to a suitable fastening near the lower part.

The operation of my invention is as follows: The gases or vapors generated in the tank 65 naturally escape at the top, passing through the packing in the chamber above and out through the openings in the cap. In case the gases should by any means take fire from the outside, the fire will be excluded from the 70 chamber by the wire-gauze cylinder surrounding it, and may be quickly extinguished by dropping the cylinder so that its flat top will cover the perforated cap of the chamber and cut off the flow of gas. In case the fire should 75 by any means reach the cap, the packing will prevent it passing through the chamber in case an explosive mixture should be contained in the tank. Such mixture, however, is not liable to be formed, as it is almost impossible 80 for a sufficient volume of air to enter through the packing. The packing may consist of sand, gravel, clay, charcoal, lime, furnace-slag, powdered coke, broken stone, sawdust, asbestos, or other similar material, either 85 singly or mixed, as may prove convenient.

It will thus be seen that by my invention all danger of explosion from the ignition of explosive gases by lightning or otherwise will be effectually prevented.

Having described my invention, what I claim, and desire to secure by Letters Patent, is—

The combination, with a tank for holding volatile liquids, of a chamber communicating 90 therewith and provided with a series of perforated disks and rings and granulated packing, the perforated cap secured to said chamber, the perforated cylinder having a flat top and conical hood, and means for elevating and depressing said cylinder, substantially as and 95 for the purpose specified.

In testimony whereof I affix my signature in presence of two witnesses.

JOHN J. FINNIGAN.

Witnesses:

WILLIAM W. McCOLLUM,
A. G. PARRISH.
